[57] CLAIM

The ornamental design for a golf theme clock, as shown
and described.

DESCRIPTION

FIG. 1 is a front elevational view of a golf theme clock
showing my new design;

FIG. 2 is a front elevational view of a second embodiment
of my new design of FIG. 1;

FIG. 3 is a front elevational view of a third embodiment
of my new design of FIG. 1;

FIG. 4 is a front elevational view of a fourth embodiment
of my new design of FIG. 1;

FIG. 5 is a front elevational view of a fifth embodiment
of my new design of FIG. 1;

FIG. 6 is a front elevational view of a sixth embodiment
of my new design of FIG. 1;

FIG. 7 is a front elevational view of a seventh embodiment
of my new design of FIG. 1; and,

FIG. 8 is a typical side elevational view of all seven
embodiments, all other side views being identical
thereto.

The rear of the golf theme clock is plain and unornamented.
